UNITED STATES PATENT OFFICE.

WINGATE S. THOMAS AND SAMUEL J. BRANSON, OF CHICAGO, ILLINOIS, ASSIGNEES
TO KNAPP BROTHERS MANUFACTURING COMPANY, OF CHICAGO, ILLINOIS, A COR-
PORATION OF ILLINOIS.

CARPET FASTENER.

Application filed November 26, 1923. Serial No. 677,135.

To all whom it may concern:

Be it known that we, WINGATE S. THOMAS and SAMUEL J. BRANSON, citizens of the United States, residing at Chicago, in the county of Cook and State of Illinois, have invented certain new and useful Improvements in Carpet Fasteners, of which the following is a specification.

This invention has to do with certain improvements in building constructions and the like. The invention has reference particularly to improvements in the means whereby the carpet is secured along its edge portion so as to keep it taut and present a finished and sightly appearance.

In certain buildings such as hotels and public places, it is the practice to remove the carpet from the floor periodically for purposes of cleaning and repairing the same. Oftentimes a certain amount of shrinkage takes place during the cleaning operation; and in order to compensate for such shrinkage, it is very customary to make the carpet of slightly larger size than the floor which it covers. In the past it has been very customary to turn the edge portions of the carpet under and tack through the double thickness of material thus provided. This procedure, however, possesses the evident disadvantage that the edge of the carpet is damaged severely and an objectionable line is formed at the point of the crease. Furthermore, in certain types of building construction, particularly those using concrete and tile floors, it becomes necessary to provide a nailing strip at the foot of the base board into which the carpet tacks may be driven.

The main object of the present invention is to provide means for securing the edge portion of the carpet in place without the use of nails or tacks or the like; in conjunction with which the use of plugs and nailing strips is also eliminated.

Another object of the present invention is to provide a type and arrangement of construction such that the desired amount of edge portion of the carpet may be accommodated beneath or within the base board or lower portion of the wall without having to fold the same under. A further object in this connection is to establish the space within which to accommodate this edge portion of the carpet without in any way weakening

or impairing the strength and durability of the wall structure.

A further feature of the invention has to do with the provision of an improved means for securing the edge portion of the carpet firmly in place so as to keep the carpet properly stretched. In this connection an object is to provide a form of clip or clamping device which is so constructed that it will take a hold of the carpet and effectively hold the same while at the same time allowing the extreme edge portion of the carpet to project into the space provided for its accommodation.

A further object in connection with the foregoing is to provide a very simple means for attachment of this carpet clamping or holding device to the lower portion of the wall structure, so that it will resist the side pull without having to use nails, bolts or other means for attachment to the floor of the building.

Still a further object in connection with the foregoing is to provide an arrangement which will lend itself admirably to use in connection with familiar and well understood implements for stretching the carpet, so that the familiar methods of performing this work may still be used in connection with the improved attaching device, herein disclosed.

Other objects and uses of the invention will appear from a detailed description of the same, which consists in the features of construction and combinations of parts hereinafter described and claimed.

In the drawings: Figure 1 shows a fragmentary transverse section through the lower portion of a wall and adjoining structure, and through the base board and nailing strip, showing one form of my improved construction applied thereto;

Fig. 2 shows a fragmentary horizontal section taken on the line 2—2 of Fig. 1, looking in the direction of the arrows, the same being an irregular section;

Fig. 3 shows a view similar to that of Fig. 1, with the exception that it illustrates a modified type of base board structure;

Fig. 4 shows another modified form of base board structure;

Fig. 5 shows a perspective view of one of the clips for holding the trough in place adjacent to the foot of the wall;

Fig. 6 shows a fragmentary cross section through the foot of a wall having applied thereto a modified form of clip;

Fig. 7 shows a view similar to that of Fig.

5 1 illustrating a modified form of construction in which the side flanges of the retaining clip are deflected outwardly at a considerable angle instead of extending straight up at the sides of the partition; and

10 Fig. 8 shows another modified construction in which a clip is provided which reaches out and embraces the outer edge of the channel so as to support the same at that point.

15 Referring first to Figs. 1 and 2, the wall is designated by the numeral 7. It is shown as being built up from tiles 8 which can be either solid or hollow as illustrated. When hollow tiles are used they establish the vertical passages 9, as clearly shown in Figs. 1 and 2.

It is very customary in tile wall constructions to place a nailing strip 10 along the lower portion of the tile, so that the base board 11 can be nailed thereto. In such case it is also customary to plaster the outer face of the tile down to the nailing strip 10, as shown at 12 in Fig. 1.

According to one feature of the present invention, we may provide longitudinally extending passage or space 13 adjacent to the outer edge of the partition, which space may be established in any convenient manner.

According to another feature of the present invention, we may provide a channel shaped strip 14 on the floor and adjacent to the foot of the wall. This strip has the upstanding flange 15 at its wall edge, and its other edge 16 is preferably curved upwards and then turned inwardly at right angles, as shown at 17. The result is that the strip 14 establishes a channel shaped passage whose upper side 18 is open and is of a width less than the interior width of the strip itself.

45 The channel shaped strip 14 is held in proper position adjacent to the foot of the wall in any convenient manner. In the arrangement shown in Figs. 1 and 2, this is done by the use of a series of clips 19. Each of these clips has an upstanding flange 20 on its back side and its front side is provided with an overturned bend or flange 21, which reaches down and engages the upstanding flange 15 of the channel strip 14. The result is that the channel strip is held in proper proximity to the wall.

Ordinarily, the clips 19 will be spaced along the wall at intervals, it being unnecessary to use them in close abutment. Furthermore, they may be of such size that they will closely embrace the thickness of the tile or the thickness of one side thereof when hollow tiles are used. In the constructions of Figs. 1 to 5 inclusive, the clips are only 65 of a width to embrace one side of the hollow

tile, but in the modified construction of Fig. 6, the clip is shown as being of sufficient width to embrace the entire thickness of the tile.

Ordinarily, the clips will be laid between 70 the lower edge of the tile and the surface of the floor. In such case it will sometimes be desirable to form one or more perforations 22 in the lower portions of the clips, so that grouting can be spread along the floor onto 75 which the tiles will be set, which grouting will reach through the openings 22 and serve to assist in holding the clips in place.

Examination of Figs. 1, 3 and 4 in particular shows that the portions 21 of the 80 clips are flared outwardly so as to in effect form a bead along the upper edge of the flange 15 of the channel strip 14. The presence of this bead together with the inturned lip 17 of the channel serves to still further 85 reduce the effective width of the opening 18 into the channel.

After the channel is in place the edge portion of the carpet is laid into the channel with its extreme edge 23 projecting upwards 90 into the space 13. Upon stretching the carpet in the proper manner a plate or plates 34 may be set down into the channel 14, above the carpet, lying therein for the purpose of locking the carpet against withdrawal from the channel. These plates 24 extend lengthwise of the channel and preferably come in relatively short sections, so that they can be set into place one after the other along the length of the channel and as the 100 consecutive carpet sections are stretched into place.

The strips 24 are of greater width than the effective opening 18 of the upper portion of the channel 14. Furthermore, the amount 105 of return of the lip 17, over the base of the channel, is such that each strip 24 may be set down into place by first forcing its outer edge and the adjacent carpet beneath the lip 17 an excessive amount which is sufficient 110 to allow the inner edge of the strip 24 together with the adjacent carpet to be pressed down past the bead 21. As soon as this action is completed and the parts released, the tension of the carpet itself working over the 115 lip 17 will tend to wedge the strip 24 backwards forcing its inner edge beneath the bead 21 and thus effectively locking the carpet in place. The action is such that the very pull of the carpet itself tends to lock 120 its edge portion more securely into the channel 14, so that increase of tension of the carpet 125 serves to improve the locking action.

When it is desired to remove the carpet, it is only necessary to grasp the projecting edge portion 23 and pull the same away from the wall. This action will force the strip 24 away from the wall until the inner edge of such strip is clear of the bead 21. As soon as this happens, the strip 24 will 130

tilt upwardly, pivoting on its outer edge, and will thus be released together with the carpet from the channel.

If desired, the inner and outer edges of the strip 24, as well as the edge of the lip 17 may be serrated or roughened so as to improve the locking action of these parts on the carpet.

If desired, also, a layer of padding 25 10 may be placed beneath the carpet and substantially up to the edge of the channel 14. When this padding is used it should preferably be of a thickness substantially the same as the height of the channel strip 14, so that 15 the carpet will pass smoothly over to the channel strip.

A finishing strip 26 of sheet metal or the like may be set into place after the carpet has been secured to the channel strip. Such 20 a finishing strip 26 when used may have its upper edge nailed to the base board 11, as indicated in Fig. 1, and its lower edge may be folded inwardly so as to pass smoothly over the carpet above the lip 17.

25 In the modified construction shown in Fig. 2, the wooden base board 11 is dispensed with and the finishing strip 27 is carried upwardly a sufficient distance to directly engage the plaster. In this case, a 30 second nailing strip 29 may be placed over the usual nailing strip 10 in order to give an additional separation from the wall, if desired.

In the modified construction of Fig. 4, we 35 have illustrated a base board 30 which reaches directly down to the position of the carpet, but the lower back side of this base board is recessed, as shown at 31, so as to provide an increased size of space for the 40 accommodation of the edge portion of the carpet.

It will be observed that where the end portion of the clip, when used, extends straight up at the side of the partition, the 45 side pull exerted thereon by the tension of the carpet tends to bend the same with respect to the body portion of the clip and cause it to straighten out. This bending action is only resisted by the stiffness of the 50 material of which the clip is made.

In those cases in which the clip is of relatively thin metal, or where the tension of the carpet may be excessive, the end of the clip may be found to bend over and allow 55 the channel to slide away from the partition.

In the modified construction of Fig. 7, the end portions of the clips are given a preliminary deflection away from the partition, 60 as shown at 33, and their end portions 34 are hooked downwardly to engage the channels. The result is that the tendency for the clips to bend is greatly reduced and it becomes possible to use thinner metal in 65 their construction.

It will also be noted that with this arrangement the channel may be set out from the base of the partition a substantial distance. Ordinarily, when the partition is set on the floor use is made of a layer of 70 grouting or the like, and oftentimes a portion of this is forced out at the sides, as shown at 35 in Fig. 7. By using clips which reach outwardly a substantial distance from the wall, so that the channels 75 may be set away from the wall, a space is provided for the accommodation of this excess grouting when present.

In the modified construction shown in Fig. 8, there is provided a clip 36 whose 80 end portions 37 are carried out around the outer edges of the channels and then turned inwardly as shown at 38 so as to embrace the upper edges of the channels. By this arrangement, the channels are given a definite and firm support at their outer edges.

We wish to point out that the channels may be held in place in any convenient manner, as by the use of clips or by originally building the channels into the structure 90 itself, or by nailing the channels to the floor or to suitable blocks or nailing strips. It is, however, of advantage to be able to set the channels in place after the plastering has been completed. This will avoid the accumulation of plaster in the channels, and the channels will be free and clear and unobstructed and ready for use for their intended work. By the use of clips which are 95 set into place during the construction of the partitions, and which are so formed that the channels can be afterwards engaged with them, it becomes possible to set the channels in place after the rough and plastering work has been completed.

100 While we have herein shown and described only certain embodiments of the feature of our present invention, still we do not intend to limit ourselves to the same, except as we may do so in the claims.

110 We claim:

1. In a building construction, the combination with a floor and a partition thereon, of an upwardly facing channel strip extending along the surface of the floor adjacent to the outside face of the partition, said channel strip having at its wall side a vertical flange and having at its opposite side an upwardly reaching flange terminating in an inwardly reaching horizontal lip, a series 115 of clips reaching between the floor and the lower edge of the partition, each clip having means for engagement with the partition and also having an outwardly curved downwardly reaching finger on its end outside of 120 the partition, said finger engaging the aforesaid vertical flange of the channel and serving to restrict the size of the channel opening at this point, a carpet laid on the floor and having its edge portion seated within 125 130

the channel and having its extreme free edge extending upwards above the channel adjacent to the partition, a substantially horizontal locking plate removably seated within the channel above the carpet therein, said locking plate in conjunction with the thickness of the carpet having a width greater than the width of the exposed opening of the channel measured between the finger and the lip aforesaid, and also having a width greater than the distance from the inner edge of the lip to the vertical channel flange at a point beneath the finger, whereby when the locking plate is in place within the channel, tension exerted on the carpet tends to force the plate sidewise against the vertical flange beneath the position of the finger, and suitable means for enclosing a longitudinally extending chamber above the position of the channel and the free edge of the carpet, substantially as described.

2. In a building construction, the combination with a floor and a partition thereon, of an upwardly facing channel strip extending along the surface of the floor adjacent to the outside face of the partition, said channel strip having at its wall side a vertical flange and having at its opposite side an upwardly reaching flange terminating in an inwardly reaching horizontal lip, a series of clips reaching between the floor and the lower edge of the partition, each clip having means for engagement with the partition and also having an outwardly curved downwardly reaching finger on its end outside of the partition, said finger engaging the aforesaid vertical flange of the channel and serving to restrict the size of the channel opening at that point, a carpet laid on the floor and having its edge portion seated within the channel and having its extreme free edge extending upwards above the channel adjacent to the partition, a substantially horizontal locking plate removably seated within the channel above the carpet therein, said locking plate in conjunction with the thickness of the carpet having a width greater than the width of the exposed opening of the channel measured between the finger and the lip aforesaid, and also having a width greater than the distance from the inner edge of the lip to the vertical channel flange at a point beneath the finger whereby when the locking plate is in place within the channel, tension exerted on the carpet tends to force the plate sidewise against the vertical flange beneath the position of the finger, substantially as described.

3. In a building construction, the combination with a floor and a partition thereon, of an upwardly facing channel strip extending along the surface of the floor adjacent to the outside face of the partition, said channel strip having at its wall side a vertical flange and having at its opposite side

an upwardly reaching flange terminating in an inwardly reaching horizontal lip, a series of clips reaching between the floor and the lower edge of the partition, each clip having means for engagement with the partition and also having an outwardly extending downwardly reaching finger on its end outside of the partition, said finger engaging the aforesaid vertical flange of the channel and serving to restrict the size of the channel opening at that point, a carpet laid on the floor and having its edge portion seated within the channel and having its extreme free edge extending upwards above the channel adjacent to the partition, a substantially horizontal locking plate removably seated within the channel above the carpet therein, said locking plate in conjunction with the thickness of the carpet having a width greater than the distance from the inner edge of the lip to the vertical channel flange at a point beneath the finger, whereby when the locking plate is in place within the channel, tension exerted on the carpet tends to force the plate sidewise against the vertical flange beneath the position of the finger, substantially as described.

4. In a building construction, the combination with a floor and a partition thereon, of an upwardly facing channel extending along the surface of the floor adjacent to the outside face of the partition, said channel having at its side away from the partition an upwardly reaching flange terminating in an inwardly reaching horizontal lip, means at the partition side of the channel reaching outwardly to overlie the channel at that point, a carpet laid on the floor and having its edge portion seated within the channel and having its extreme free edge extending upwards above the channel adjacent to the partition, a substantially horizontal locking plate removably seated within the channel above the carpet therein, said locking plate in conjunction with the thickness of the carpet having a width greater than the distance from the inner edge of the lip to the partition side of the channel at a point beneath the overlying projection aforesaid, whereby when the locking plate is in place within the channel, tension exerted on the carpet tends to force the plate sidewise against the channel wall adjacent to the partition, and suitable means for enclosing a longitudinally extending chamber above the position of the channel and the free edge of the carpet, substantially as described.

5. In a building construction, the combination with a floor and a partition thereon, of an upwardly facing channel extending along the surface of the floor adjacent to the outside face of the partition, said channel having at its side away from the partition an upwardly reaching flange ter-

minating in an inwardly reaching horizontal lip, means at the partition side of the channel reaching outwardly to overlie the channel at that point, a carpet laid on the 5 floor and having its edge portion seated within the channel and having its extreme free edge extending upwards above the channel adjacent to the partition, a substantially horizontal locking plate removably seated 10 within the channel above the carpet therein, said locking plate in conjunction with the thickness of the carpet having a width greater than the distance from the inner edge of the lip to the partition side of the 15 channel at a point beneath the overlying projection aforesaid, whereby when the locking plate is in place within the channel, tension exerted on the carpet tends to force the plate sidewise against the channel wall adjacent to the partition, substantially as described.

6. The combination with a floor and a partition, of means for holding the edge portion of a carpet adjacent to the partition

comprising a longitudinally extending member having a carpet contacting edge facing against the direction of carpet tension, a locking device having a part engaging the exposed surface of the carpet at a point beneath said contacting edge, and means preventing disengagement of said locking device from the carpet by a direct movement upwards past said edge, substantially as described. 25

7. Means for gripping the edge portion 30 of a carpet in place on a floor, comprising two edged members located adjacent to each other with their edges facing in opposite directions and having their edge portions overlapped, a carpet passing over one of 35 said edges and between the opposing edges and beneath the other edge, and means for holding said members against lateral displacement with respect to each other by the tension of the carpet, substantially as de- 40 scribed. 45

SAMUEL J. BRANSON.
WINGATE S. THOMAS.
